UNITED STATES PATENT OFFICE.

JAMES N. SCULLY AND CARLISLE A. LINCOLN, OF BUFFALO, NEW YORK, ASSIGNORS TO THE HOUDAILLE COMPANY, OF BUFFALO, NEW YORK, A CORPORATION OF DELAWARE.

SECTIONAL SPRING COVER.

Application filed November 27, 1923. Serial No. 677,228.

To all whom it may concern:

Be it known that we, JAMES N. SCULLY and CARLISLE A. LINCOLN, citizens of the United States, residing at Buffalo, in the county of Erie and State of New York, and Buffalo, in the county of Erie and State of New York, respectively, have invented certain new and useful Improvements in Sectional Spring Covers; and we do hereby 5 declare the following to be a full, clear, and exact description of the invention, such as will enable others skilled in the art to which it appertains to make and use the same.

The present invention relates to devices 10 for covering or enveloping vehicle springs, more particularly described as spring casings or covers.

The object of the present invention is to improve and redesign spring covers in a 15 manner to improve the appearance and fit of the cover when applied to a spring and in addition to form a better closure for the lubricant and permit the employment of a minimum quantity of lubricant.

With this object in view the various features of the invention consist in certain 20 novel features of construction, combinations and arrangements of parts hereinafter described and claimed, the advantages of 25 which will be obvious to those skilled in the art from the following description.

In the accompanying drawings illustrating 30 the preferred form of the invention Fig. 1 represents a top plan view of the improved spring cover applied to one-half of a vehicle spring; Fig. 2 is a side elevation of the cover shown in Fig. 1; Fig. 3 is a bottom plan view of the cover shown in Fig. 1; Fig. 4 is a detail illustrating a perspective view of one 35 of the closure plates adapted to join the sections of the cover adjacent the spring clip; Fig. 5 is a detail illustrating a section of a portion of the cover adjacent the spring clip illustrating the manner in which the sections 40 of the cover are joined by the closure plate; and Fig. 6 is a cross section of the cover 45 through the spring clip.

The cover comprised in the present invention is formed of a series of sections which 50 are indicated at 10, 12 and 14, these sections conforming generally to the shape and dimensions of that portion of the spring which they enclose, the sections extending between the clips which serve to bind the several

leaves of the spring together and forming in 55 conjunction with the closure plates a substantially continuous casing from the central portion of the spring outwardly to the end. Each of the sections is wrapped about the spring and secured in place by a lacing 60 cord 16 which passes through lacing hooks 18 secured to opposite edges of the casing. The various sections of flexible material are united at the areas adjacent the spring clips to form a substantially continuous casing by 65 closure members or plates having the general form indicated at 20 in Fig. 4. Each of these closure members comprises a relatively flat top portion 22 provided with depending wing portions 24 to cause the closure 70 to extend across the top and down the sides of the spring. The closure is intended to be mounted beneath a spring clip of usual form which consists of a U-shaped yoke member 26 of flat stock having the 75 upper ends joined by a clip bolt 28. The closure is applied by removing the bolt from the spring clip and inserting the closure with the depending wings extending down the sides of the spring inside of the legs of 80 the yoke, the latter contacting with the depression or recessed portion 30 formed in the closure. Thereafter the insertion of the clip bolt 28 which lies in the depression 30 formed in the top of the closure locks the 85 latter in position and clamps the opposite edges of the closure firmly to the adjacent ends of the flexible casing which has already 90 been applied to the spring. In order to increase the sealing effect between the closure and sections of the casing, the closure is provided with projections 32 which extend below the wings 24 and are adapted to be turned under the bottom of the spring, as indicated clearly in Fig. 3, to bind the ends 95 of the casing. In order to augment the sealing effect at the bottom of the spring, a packing strip of felt or similar material indicated at 34 may be inserted between the bottom face of the spring and the edge of 100 the cover, as indicated clearly in Figs. 2 and 5. The outer ends of the two casing sections which abut respectively the central portion and the end of the vehicle spring may be provided with a packing strip of felt 105 or similar material indicated generally at 40 and 42, these strips serving to prevent leakage of lubricant lengthwise of the spring.

It will be evident to those skilled in the art from the foregoing description that the present type of cover may be fitted tightly about the vehicle spring to present a neat finished appearance and that the provision of the closure members joining adjacent sections throughout the area of the spring clips not only seals the sections but in addition adds a further finish to the cover.

10 Furthermore the closure member may be made of sufficient length to accommodate a considerable variation in spring length and permit sections of the same length to be employed where the length of the spring varies or the distance between the spring clips themselves or between the clips and the ends of the spring varies.

15

The spring cover shown in the illustrated embodiment of the invention may be provided with any conventional device for inserting lubricant within the cover or may be employed merely as a protector for the spring and the lubricant applied to the spring either in the form of grease or a 20 heavy oil before the application of the cover. Furthermore the closure members or plates, so called, may be constructed of metal or non-metallic material, providing that the closure is sufficiently stiff and rigid to exert the necessary sealing effect at the ends of the flexible sections and impart the desired finish and appearance to the cover.

25

30 While it is preferred to employ the spe-

cific construction and arrangement of parts shown and described, it will be understood that this construction and arrangement is not essential except so far as specified in the claims and may be changed or modified without departing from the broader features of the invention.

40 The invention having been described, what is claimed is:

1. A spring cover comprising a casing of flexible material wrapped about the body of a spring, and a closure member partially 45 surrounding the spring adjacent the clip and bearing upon the casing at opposite sides of the clip to substantially seal the latter in the region of the clip.

2. A spring cover comprising a flexible 50 casing wrapped about the body of the spring, and a closure plate interposed between the top and sides of the spring and the spring clip and bearing upon the casing at opposite sides of the clip, the closure 55 member being locked in place by the clip.

3. A spring cover comprising a flexible casing wrapped about the body of the spring, a closure member having a depression therein for the reception of the spring clip and clip bolt, the closure member being interposed between the body of the spring and the clip and adapted to bear upon the casing at opposite sides of the clip.

JAMES N. SCULLY.
